UNITED STATES PATENT OFFICE.

HERMAN A. DAVENPORT, OF BROCKTON, MASSACHUSETTS, ASSIGNOR TO UNITED SHOE MACHINERY COMPANY, OF PATERSON, NEW JERSEY, A CORPORATION OF NEW JERSEY.

SOLE-PRESSING MACHINE.

1,251,869.

Specification of Letters Patent. Patented Jan. 1, 1918.

Application filed April 24, 1916. Serial No. 93,171.

To all whom it may concern:

Be it known that I, HERMAN A. DAVENPORT, a citizen of the United States, residing at Brockton, in the county of Plymouth and 5 State of Massachusetts, have invented certain new and useful Improvements in Sole-Pressing Machines; and I do hereby declare the following to be a full, clear, and exact 10 description of the invention, such as will enable others skilled in the art to which it appertains to make and use the same.

The present invention relates to machines for shaping the soles of boots and shoes, and more particularly to machines of this type 15 employed for laying the sole upon a lasted boot or shoe.

In a certain type of machine employed for laying the soles of boots and shoes a flexible pressing pad of rubber or other suitable 20 material is supported at a plurality of points by mechanism which is arranged to equalize the pressure exerted by all portions of the pad. This type of pressing pad and supporting mechanism is disclosed in the patent 25 to Davenport, No. 942,133, dated December 7, 1909, and the sole laying machine in which the pressing pad is embodied is disclosed in the patent to Davenport, No. 1,066,473, dated July 8, 1913.

30 It is desirable, under certain conditions, to relieve the pressure exerted by the pressing pad upon some portion of the shoe sole, more particularly the toe, and it is the object of the present invention to provide certain 35 improvements in a machine of the above described type which will enable the pressure upon different portions of the shoe sole to be regulated within desired limits.

To this end a feature of the invention 40 contemplates the provision in a sole laying machine having a shoe supporting jack, a coöperating flexible pressing pad, and mechanism for supporting the pad arranged to equalize the pressure exerted by all portions 45 of the pad, of a pressure regulating member engaging with the pad adjacent a portion of the shoe sole to relieve the pressure exerted by the pad upon that portion of the sole.

50 Still further features of the invention consist in certain novel features of construction, combinations and arrangements of parts hereinafter described and claimed, the ad-

vantages of which will be obvious to those skilled in the art from the following description.

55 In the accompanying drawings illustrating the preferred form of the invention Figure 1 represents a partial side elevation of a machine embodying the features of the invention, Fig. 2 is a detail illustrating the toe pressure regulating member, and coöperating toe rest, and Fig. 3 is a detail illustrating an elevation of the pressure regulating member and toe rest shown in Fig. 2. 60

65 In laying a flat sole upon the bottom of a lasted boot or shoe, it is essential that the sole shall engage with substantially all portions of the shoe bottom, and be shaped approximately thereto. In order to perform 70 this sole laying operation properly, especially upon shoes having rounded or steep shanks, it is desirable that the pressure exerted upon the shank portion of the sole shall be greater than the pressure exerted upon 75 the toe or heel portions of the sole. In the type of machine to which the present invention relates, the pressure exerted by all portions of the sole laying pad is automatically 80 equalized, and in some instances it is found that a pressure sufficient to properly secure 85 the shank portion of the sole to the shoe bottom is too heavy for the toe portion of the sole. It will be obvious to those skilled in the art that too great a pressure exerted upon the ends of the sole, more particularly 90 the toe, will tend to cause the toe to sink into the flexible pad, rounding over the projecting margins of the sole. In the present invention means are provided for relieving 95 the pressure exerted by the pad upon the toe of the shoe without diminishing the pressure exerted upon the other portions of the sole. To this end a pressure regulating member is 100 provided with a pad engaging face positioned at substantially the height of the shoe sole, and arranged to engage with the pad adjacent the toe portion of the sole. In the illustrated embodiment of the invention a foot is secured to the toe post and has a pad engaging face surrounding the toe portion of the shoe to resist the thrust exerted by this portion of the pad. The foot is supported 105 unyieldingly, and has the added function of causing the pad to automatically exert a greater pressure than otherwise upon those

portions of the sole not protected by the foot. This will be obvious to those skilled in the art when it is considered that the movement of the toe portion of the pad is 5 positively limited by the foot, and the pad as a whole will therefore pivot about the toe and tend to bear upon the shank and remaining portions of the sole with an added pressure.

The machine comprises the usual stationary head 1 mounted at the upper end of a frame 2, and slidingly supporting a heel post 3 and coöperating toe post 4. The shoe sole is engaged from beneath by a flexible pressing pad 10 supported at a plurality 15 of points by pad supports 11 which are individually supported by a system of equalizing levers mounted upon a block 12 which is yieldingly supported in a pad box 14. The pad box and pad as a whole are moved vertically upon the frame 2 to cause the pressing pad to engage with the shoe sole in the usual manner. This mechanism is fully shown and described in the patents to 20 Davenport hereinbefore referred to.

25 The pressure normally exerted upon the toe of the shoe is relieved by a foot 15 secured to the lower end of the toe post 4, and having a pad engaging face 16, as shown clearly in Figs. 2 and 3 positioned at approximately the height of the shoe sole, and curved to conform to the curvature of the toe portion of the shoe. The pad engaging face of the foot serves to resist the thrust of the pad upon that portion of the sole 30 which is adjacent to the foot, and cause an added pressure to be exerted upon other portions of the sole. A foot 15 is provided with a grooved lip 17 which engages with a correspondingly formed face upon the toe post 4, and is secured thereto by a threaded fastening 18. The opposite face of the toe post is provided with a plate 19 pivoted thereto at 20 and secured at its lower end to the foot by a threaded fastening 21. The 45 toe portion of the lasted shoe is supported by a toe rest 23 of flexible material secured to the lower end of a slide 24 movable vertically in the foot, and normally retained in a depressed position by a spring 25 received 50 in a recess 26 formed in the foot, and engaging with the top of the slide. The toe rest is retained against angular movement by a pin 27 projecting laterally from the slide, and received in a vertical slot 28 formed in the 55 foot. The toe rest 23 is provided with a metal back plate 29 supported upon the reduced end of the slide 24 and the toe rest and back plate are secured to the slide by a fastening 30 threaded into the end of the 60 slide.

While it is preferred to employ the specific construction and arrangement of parts shown and described, it will be understood that this construction and arrangement is not essential, except so far as specified in 65 the claims, and may be changed and modified without departing from the broader features of the invention.

The invention having been described, what is claimed is:

70 1. A sole laying machine comprising a shoe supporting jack, a flexible pressing pad, means for yieldingly supporting the pad arranged to equalize the pressure exerted by all portions of the pad, and a pressure regulating member carried by the jack and engaging with the pad adjacent to a portion of the shoe sole to relieve the pressure exerted by the pad upon that portion of the sole.

75 2. A sole laying machine comprising a shoe supporting jack, a flexible pressing pad, means for yieldingly supporting the pad arranged to equalize the pressure exerted by all portions of the pad, a pressure regulating member having a pad engaging face positioned at the level of the shoe sole and adjacent one portion of the sole, and arranged to relieve the pressure exerted by the pad upon that portion of the sole, and means for 80 unyieldingly supporting the pressure regulating member.

85 3. A sole laying machine comprising a flexible pressing pad, means for supporting the pad arranged to equalize the pressure exerted by all portions of the pad, a heel post, and coöperating toe post for supporting a lasted shoe, and a pressure regulating member secured to the toe post and surrounding the toe portion of the shoe to relieve the 90 pressure exerted by the pad upon that portion of the sole.

100 4. A sole laying machine comprising a heel post and coöperating toe post for supporting a lasted shoe, a flexible pressing pad for engaging with the shoe bottom, means for supporting the pad, and a curved foot secured to the toe post and arranged to engage with the pad about the toe portion of the shoe.

110 5. A sole laying machine comprising a heel post and coöperating toe post arranged to support a lasted shoe, a flexible pressing pad engaging with the shoe bottom, means for supporting the pad, a curved foot secured to the lower end of the toe post, and having a pad engaging face surrounding the toe of the shoe, and a toe rest yieldingly supported in the foot.

115 HERMAN A. DAVENPORT.
